UNITED STATES PATENT OFFICE

CLINTON J. PHARE, OF CLEVELAND, OHIO, ASSIGNOR TO HOYT V. BRIGHT, OF CLEVELAND, OHIO

SHOCK ABSORBING MEANS FOR TURNSTILES

Application filed April 26, 1928. Serial No. 272,919.

This invention relates to turnstiles and has for its main object to provide an automatic turnstile, in which the head or hub carrying the arms will be rotated by a person pressing against the arms in passing through the turnstile and after initial manual movement the head will continue to rotate automatically to carry the arms to their next positions.

Another object of the invention is to provide an automatic turnstile, in which the end of the movement of the arms is retarded so as to make the turnstile quiet in its operation.

A further object of the invention is to provide a turnstile of the above character of simple and practical construction.

In order that the invention may be clearly understood, the same will be hereinafter fully described in connection with the accompanying drawings, and the novel features thereof will be particularly pointed out in the appended claims.

In the drawings, similar characters of reference are used to indicate corresponding parts.

Figure 1 is a front elevation of a turnstile constructed in accordance with my invention.

Fig. 2 is a plan view thereof.

Fig. 3 is a side elevation, on an enlarged scale of the operating mechanism portion of the turnstile,

Fig. 4 is a similar view but at a right angle thereto, certain parts being broken away to better show the construction,

Fig. 5 illustrates the relative positions of the cranks at the opposite sides of the turnstile,

Fig. 6 is a sectional elevation taken on line 6-6 of Fig. 7,

Fig. 7 is a plan sectional view taken on line 7-7 of Fig. 6,

Fig. 8 is a bottom plan view of a casing,

Fig. 9 is a longitudinal sectional view of the cylinder cap, on an enlarged scale, taken through the controlled inlet thereof,

Fig. 10 is a sectional view illustrating the vent in the cylinder cap, and

Fig. 11 is a sectional view illustrating the vent and by-pass in the bottom of each cylinder.

Referring to the drawings, 1 represents a tapering hollow pedestal having a base 2. Within the pedestal and just below its top edge 3 is a spider 4 and another spider 5 therebelow, in the centers of which is fixed a vertical shaft 6. The top peripheral edge 3 of the pedestal is provided with transversely aligning recesses 7 and 8 for receiving horizontal bars or tongues as at 9 formed integrally with the under side of a disc 11 provided with a central opening 12 for the shaft 6 and having an upstanding peripheral flange 13. The disc 11 is thus held against rotation, and at the center thereof is an upstanding boss 14, upon the top of which rests a ball-bearing cage 15 for rotatably supporting an inverted bowl-shaped casing 16 having a central opening 17 through its top 18 for the shaft 6.

Fixed to the top 18 of the casing 16 and rotatably mounted upon the shaft 6 is a hub 19 carrying a frame 20 and arms 21. For preventing backward rotation of the arms 21, the following mechanism is provided. A locking plate 22 having an opening 23 for receiving the boss 14 is adapted to loosely rest upon the surface 24 of the disc 11. Pivotedly supported by the locking plate 22 at 25 and 26 are a pair of oppositely arranged pawls 27 and 28 having toothed ends 29 and 30 which are adapted to engage vertical teeth 31 on the inner surface of the upstanding peripheral flange 13 of the stationary disc 11. The pawls 27 and 28 have right angular and inwardly extending heads indicated by 32 and 33, which are adapted to be engaged by side edges of transversely aligning vertical recesses 34 and 35 of a depending circular flange 36 formed integrally with the top 18 of the casing 16. Stops 37 and 38 carried by the disc 11 are adapted to be engaged by the pawls 27 and 28 when the casing 16 rotates clockwise. When the casing 16 rotates in the opposite direction, the pawls 27 and 28 are caused to swing away from the stops 37 and 38 and their toothed ends 29 and 30 to engage the teeth 31 and thereby prevent backward rotation of said casing and the arms 21 carried thereby.

In order to cause automatic rotation of the

arms 21 after initial movement thereof by a person pressing thereagainst, and also to automatically check said movement at its end to eliminate noise in operation and to stop the rotation of the arms on the quarter turn, the mechanism now to be described is provided. Depending from and fixed to the casting 16 by bolts at 39 is a circular downwardly flanged plate 40 having a large central opening 41 for clearing the pedestal 1, and formed integrally with and depending from said plate is a ring-gear 42. Vertically arranged base plates 43 and 44 having hollow horizontal trunnions 45 and 46 for swingingly supporting cylinders 47 and 48 are secured to the pedestal 1 by bolts 49 and 50. Slidably mounted in the cylinder 47 is a piston 51 having a rod 52 which extends through a central opening 53 of a cap 54 for the cylinder. To the projecting end of the rod 52 is fixed a head 55, which supports a bar 56 pivotally connected to the crank-pin 57 of a crank 58. Said crank is fixed to the shaft 59 of a bevel pinion 60, and said shaft is rotatably supported in the sides of a bracket formed integrally with the upper end of the base plate 43. The bevel pinion 60 and a similar bevel pinion 61 supported by the base plate 44 mesh with the ring-gear 42 and the cranks 58 and 62 are fixed to the shafts thereof at right angular positions relative to each other. A pair of contractual coiled springs 63 and 64 extend from cross-arms 65 and 66 at the base of the cylinder 47 to cross-arms 67 and 68 carried by the head 55 tend to force the piston rod 52 downwardly for causing continued rotation of the turnstile arms 21 to the quarter position after the initial manual operation thereof. The arms of the turnstile stop on the quarter position due to the crank 58 returning to its original downward and vertical position and the coiled springs 63 and 64 pulling directly against the dead center thereof. The cylinder 48 is similar to the cylinder 47 and slidably mounted therein is a piston 69, the rod 70 of which is pivotally connected to the crank 62, but there are no coiled springs for actuating the piston rod downwardly.

When the arms 21 of the turnstile are almost to the limit of the quarter turn, the rotation thereof is checked by the pistons 51 and 69 moving downwardly against air pressure in the cylinders 47 and 48. At the beginning of the upward movement of said pistons, air is admitted to the cylinders below each piston through a vent 71 which registers with a slot 72 of the hollow trunnion 45 or 46. The vent 71 is enlarged at 73 to provide a chamber and a seat for a ball check valve 74. A vented plug 75 is fixed in and closes said chamber. In the downward movement of the pistons, the vents 71 are closed by the check valve 74, and the air is forced out of each cylinder slowly through a by-pass 76

of proper size to produce the desired movement of the arms 21 of the turnstile. The by-pass 76 registers with a slot 77 of the hollow trunnions, and an opening 78 establishes free communication between said trunnions and the atmosphere. A vent 79 with check valve 80 is provided in each of the caps 54, and air escapes from the cylinders through these vents when the pistons move upwardly but is prevented from entering on the downward movement of the pistons. In order to break the vacuum above the pistons so that the pistons may move downwardly, an inlet opening 81 is provided in each cap 54, and said inlet openings are closed by an adjustable valve as for instance 82 for admitting air at a desired speed.

Operation: Assuming that the arms 21 of the turnstile are at rest on the quarter turn and also the other parts are as shown, and a person walking through, indicated by the arrow, presses against the left arm of the turnstile. Said arms will be rotated by said pressing action just beyond one-eighth of a revolution, which movement will cause the ring-gear 42 to rotate the bevel pinions 60 and 61 to actuate the cranks 58 and 62 just beyond one-half of a revolution. At the same time, the piston 51 will travel upwardly for its full movement and the piston 69 will travel downwardly from its central position and then upwardly to the same position. As soon as the crank 58 passes the upper dead center, the coiled springs 63 and 64 will force the piston rod 52 downwardly thereby automatically continuing the rotation of the arms 21 of the turnstile. As the piston travels downwardly, it works against and forces air through the by-pass 76, which has a cushioning effect upon and checks the movement of the arms of the turnstile to their quarter positions. The arms of turnstile come to a stop at their quarter positions when the crank 58 has returned to its original or lower dead center position.

From the drawings and description, it will be readily seen that after initial manual rotation of the arms of the turnstile, the movement thereof will be continued and come to a stop at their quarter positions, and that before the arms come to a stop, the movement thereof will be gradually retarded and checked thereby preventing noise in operation of the turnstile.

It will be understood that slight changes in the details of construction for carrying out my invention may be made within the scope of the claims.

Having fully described my invention, what I claim is:

1. In a turnstile, the combination of a pedestal, arms rotatably supported by the pedestal, means for causing automatic rotation of the arms and for stopping the rotation thereof at a predetermined position, and

means for retarding the movement of the arms prior to the stopping thereof.

2. In a turnstile, the combination of a pedestal, arms rotatably supported by the pedestal, means for causing automatic rotation of the arms and for stopping the rotation thereof at a predetermined position, and pneumatic means for cushioning the movement of the arms prior to the stopping thereof.

3. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, and means for causing rotation of the crank to cause rotation of said pinion.

4. In a turnstile, the combination of a pedestal, a casing rotatably supported by the pedestal, arms carried by the casing, a ring-gear fixed to the casing, a pinion in mesh with the ring-gear, means for supporting the pinion, and a pair of springs for causing automatic rotation of the pinion after initial manual movement thereof and for stopping the rotation of said pinion at a predetermined point.

5. In a turnstile, the combination of a pedestal, a casing rotatably supported by the pedestal, arms carried by the casing, a ring-gear fixed to the casing, a pinion in mesh with the ring-gear, means for supporting the pinion, means for causing automatic rotation of the pinion after initial manual movement thereof and for stopping the rotation of said pinion at a predetermined point, and pneumatic means for cushioning the movement of said pinion prior to the stopping thereof.

6. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, a rod pivotally connected to the crank, and means tending to force the rod in one direction.

50 7. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, a rod pivotally connected to the crank, the rod being normally in alignment with the crank, and springs tending to force the rod in one direction.

60 8. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, a

cylinder, the cylinder being pivotally supported, a piston in the cylinder, a rod fixed to the piston and being pivotally connected to said crank, means tending to force said rod in one direction, a vent in the cylinder at each side of the piston, valves adapted to close the vent upon movement of said rod, and by-passes in the cylinder at each side of the piston for controlling the outlet of air from the cylinder.

70 9. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, a cylinder, the cylinder being pivotally supported, a piston in the cylinder, a rod fixed to the piston, the rod being pivotally connected to said crank and in alignment therewith when the piston is at the lower end limit of the cylinder, arms extending laterally from said rod, arms extending laterally from the cylinder, springs connected to said arms tending to force said rod downwardly, a vent in the cylinder at each side of the piston, valves adapted to close the vent upon movement of said rod, and by-passes in the cylinder at each side of the piston for controlling the outlet of air from the cylinder.

75 10. In a turnstile, the combination of a pedestal, a casing rotatably supported by the pedestal, arms carried by the casing, a ring-gear fixed to the casing, pinions in mesh with the ring-gear, the pinions being supported from the pedestal, cranks for operating the pinions, the cranks being at right angles relative to each other, cylinders, the cylinders being pivotally supported from the pedestal, pistons in the cylinders, rods fixed to the pistons, said rods being pivotally connected to said cranks, arms extending laterally and in opposite directions, from one of said rods, arms extending laterally from the cylinder below the first mentioned arms, springs connected to said arms tending to force said rod downwardly, a vent in the cylinder at each side of the piston, valves adapted to close the vent upon movement of said rod, and by-passes in the cylinder at each side of the piston for controlling the outlet of air from the cylinder.

80 11. In a turnstile, the combination of a pedestal, a casing rotatably supported by the pedestal, arms carried by the casing, a ring-gear fixed to the casing, a pinion in mesh with the ring-gear, means for supporting the pinion, a crank for operating said pinion, a cylinder, the cylinder being pivotally supported, a piston in the cylinder, a rod fixed to the piston and being pivotally connected to said crank, means tending to force said rod in one direction, vents in the cylinders at each side of the pistons, valves adapted to close the vents upon downward movement of said rods,

by-passes in the cylinders below said pistons for controlling the outlet of air from the cylinders, inlets in the cylinders above the pistons, for admitting air to the cylinders, and means for controlling the air admitted through said inlets.

12. In a turnstile, the combination of a pedestal, a shaft supported by the pedestal, a disc on the shaft and supported by the pedestal, the disc having a central boss and an upstanding peripheral flange, said flange having teeth, a plate rotatably mounted upon said boss, a pair of pawls pivotally supported by the plate, the pawls having right angular ends, a casing rotatably mounted upon said shaft and resting upon said boss, the casing having means adapted to engage said right angular ends of said pawls to cause the pawls to engage said teeth to prevent backward rotation of the casing, a ring-gear fixed to the casing, a pinion in mesh with the ring-gear, means for supporting the pinion, a crank for operating said pinion, and means for causing the rotation of the crank to cause rotation of said pinion.

In testimony whereof I affix my signature.
CLINTON J. PHARE.
